UNITED STATES PATENT OFFICE

148,288

DESIGN FOR A RADIO RECEIVING SET

Francis A. Dawson, Kokomo, Ind., assignor to
Kingston Products Corporation, Kokomo, Ind.,
a corporation of Indiana

Application February 1, 1946, Serial No. 126,143

Term of patent 7 years

(Cl. D56—4)

To all whom it may concern:

Be it known that I, Francis A. Dawson, a citizen of the United States and a resident of the city of Kokomo, in the county of Howard and State of Indiana, have invented a new, original, and ornamental Design for a Radio Receiving Set, of which the following is a specification, reference being had to the accompanying drawing forming a part thereof.

On the drawing:

Figure 1 is a top plan view of the radio receiving set, or similar article, showing my new design.

Figure 2 is a front elevational view thereof, the hatching on the dial indicating transparency, and the cross-hatching indicating fabric, which is visible through the dial.

Figure 3 is a side elevational view thereof.

Figure 4 is a fragmentary cross sectional view

taken on the line IV—IV of Figure 2 looking in the direction indicated by the arrows and showing the relationship of the transparent dial to the fabric therebehind.

I claim:

The ornamental design for a radio receiving set, as shown.

FRANCIS A. DAWSON.
